UNITED STATES PATENT OFFICE.

LEWIS M. ELWELL, OF ZANESVILLE, OHIO.

DESIGN FOR A MONUMENT.

43,662.

Specification for Design.

Patented Feb. 25, 1913.

Application filed August 25, 1911. Serial No. 646,072. Term of patent 7 years.

To all whom it may concern:

Be it known that I, LEWIS M. ELWELL, a citizen of the United States, residing at Zanesville, county of Muskingum, and State of Ohio, have invented a new, original, and ornamental Design for Monuments, of which the following is a specification, reference being had to the accompanying drawing, forming part thereof.

The figure is a perspective view of the monument, showing my new design.

I claim:

The ornamental design for a monument, as shown.

LEWIS M. ELWELL.

Witnesses:

G. C. BUXTON,
ROY P. HOOK.
